IMPEDANCE TRANSFORMER

Clarence W. Hansell, Rocky Point, N. Y.,
assignor to Radio Corporation of America, a
corporation of Delaware

Application April 14, 1928. Serial No. 269,939

5 Claims. (Cl. 178—44)

This invention relates to impedance transformers, and more particularly to a novel transformer consisting of a line the inductance and capacitance characteristics of which are varied to obtain the desired impedance transformation.

At high frequencies it becomes exceedingly difficult to construct efficient transformers, and accordingly the tendency is towards various forms of direct coupling which, by a suitable 10 combination of reactances, serve to produce the desired impedance change. These methods are accompanied by the disadvantage that the degree of coupling and transformation varies with the frequency, a difficulty which is experienced to a 15 considerable degree even in the range of lower frequencies where the use of transformers is practicable, and which is still more marked with directly coupled reactance arrangements:

It is a primary object of my invention to provide 20 an impedance transformer which is independent of frequency, or otherwise stated, which experiences no resonance phenomena. This I propose to do by coupling the circuits through a natural or artificial line the inductance and 25 capacitance characteristics of which are such that the impedance at one end equals one of the desired impedances, and the impedance at the other end equals the other desired impedance, while the impedances at points intermediate the 30 ends vary exponentially between the desired end impedances.

The underlying idea may be explained by its analogy with the now well known exponential horn, which is no more than an air impedance 35 changing device. At the diaphragm or small end of the horn there is a high air impedance, while at the mouth or large end of the horn there is a very low air impedance, and the horn serves to change from one to the other. By varying the 40 cross section of the horn exponentially along its length it is found that resonance phenomena within the horn may be effectually prevented. In a similar way, I propose to couple two electrical circuits of differing electrical impedances with 45 an impedance changing device which transforms the impedance gradually and progressively in amounts which vary in exponential or geometric progression, so that the impedance transformer is aperiodic.

50 The invention is described more in detail in connection with the accompanying drawing, in which

Figure 1 shows an artificial line built up of a number of sections each having series inductance and shunt capacitance;

Figure 2 shows a similar arrangement having series capacitance and shunt inductance;

Figure 3 indicates a line and antenna coupled together by an aperiodic transformer employing no lumped reactances;

Figure 4 is a modification; and

Figure 5 shows interstage coupling for exceedingly high frequencies.

Referring to Figure 1 there is an artificial line made up of a number of sections comprising 65 series inductances 2 and shunt condensers 4. Now in accordance with the present invention if a total impedance change from R to r is required, and if X sections are to be employed, the impedance ratio for each section, N , is made equal 70 to the total impedance ratio, $\frac{r}{R}$, raised to an exponent which is the reciprocal of the number of sections, X . In this way, as can be seen from the notation below Fig. 2, the impedance is varied exponentially along the artificial line, so that after five sections, as shown in Figure 1 as a simple illustration, the impedance is N^5R , and since this is to be equal to r , it is obvious that N equals the 5th root of the ratio $\frac{r}{R}$. 80

The arrangement shown in Figure 1 may be explained more in detail as follows. It is well known that the surge impedance of a line having series inductance and shunt capacity is approximately 85

$$z = \sqrt{\frac{L}{C}}$$

In case the impedance is to be stepped up the 90 value of L may be increased, or the value of C decreased, or both. When an artificial line, consisting of lumped inductances and capacitances is used, instead of a natural line, the resulting 95 sections are low pass filter sections, and it is necessary to so select the reactance values that the cut off frequency lies far above the frequency range with which the line is to be used as a transformer. The cut off frequency is given by the expression 100

$$f = \frac{1}{\pi\sqrt{LC}}$$

It should be noticed that if the impedance along the line is varied by increasing L and decreasing C each by the desired factor the impedance of the line will be increased by that factor, inasmuch as 105

$$z = \sqrt{\frac{L}{C}}$$

and at the same time the cut off frequency will remain constant, inasmuch as the product LC will remain constant.

The legend "L" appearing in the equations 115 above, represents the inductance per section or per unit of length of an artificial line. With reference to Fig. 1 for example, "L" is the portion of the inductance per section of the line which may be assigned to each of the capacities. Thus, 120

waves, and if it is a receiver, the line is terminated because the purpose of the antenna is to receive. It is necessary to obtain maximum voltage at the terminals of the antenna.

In place of strips of metal such as illustrated in Figure X, a structure of high resistivity conductivity may be employed such an arrangement for the conductors is illustrated in Figure Y. It is shown here in a two wire form, but the conductors may be employed, and the insulation therebetween may be combined,

The desired change in either inductance or
capacitance of both may be obtained by
joining a conductor with some dielectric
material or insulator.

There is a definite relationship between the amount of energy available to the plant and the amount of energy available to the animal.

radio frequency
whose terminals are

posed conductors whose areas vary substantially continuously along the length of the device, the impedance of said device varying exponentially along its length whereby its terminals present impedances having values which are equal to the impedances to be faced.

3. In combination, a pair of radio frequency electrical circuits having different impedances, an impedance matching device whose terminals are adapted to connect together said pair of circuits, each terminal of said device having an impedance whose value corresponds to the impedance of the electrical circuit which it faces, said device comprising a plurality of superposed conductors the impedance of which as a whole tapers continuously along the length of the device.

4. A radio frequency impedance matching device whose terminals are adapted to face different impedances comprising a plurality of super-

posed conductors, at least one of which varies smoothly and continuously in mass along its length, the impedance of said device tapering substantially continuously along its length whereby its terminals present impedances having values which are equal to the impedances to be faced.

5. In combination, a radio transmitter having a predetermined impedance, a radiating antenna having a different impedance, and a radio frequency impedance matching device therebetween whose terminals are adapted to face said two different impedances comprising a plurality of conductors, at least one of which varies in mass substantially continuously along its length, the impedance of said device tapering substantially continuously along its length whereby its terminals present impedances having values which are equal to the respective impedances to be faced.
